UNITED STATES PATENT OFFICE.

OLIVER PIERCE GREENSTREET, OF BAXTER SPRINGS, KANSAS, ASSIGNOR TO
OKLAHOMA ZINC PRODUCTS CO., OF QUAPAW, OKLAHOMA, A CORPORATION
OF OKLAHOMA.

LUNCH-BUCKET.

1,324,891.

Specification of Letters Patent. Patented Dec. 16, 1919.

Application filed May 3, 1919. Serial No. 294,488.

To all whom it may concern:

Be it known that I, OLIVER PIERCE GREEN-
STREET, a citizen of the United States, resid-
ing at Baxter Springs, in the county of
5 Cherokee and State of Kansas, have invent-
ed certain new and useful Improvements in
Lunch-Buckets, of which the following is a
specification, reference being had to the ac-
companying drawings.

10 This invention relates to certain improve-
ments in lunch buckets, and it is an object
of the invention to provide a device of this
general character including novel and im-
proved means whereby the interior of the
15 bucket may be effectively and thoroughly
ventilated in order to maintain the same in
a sanitary condition.

Another object of the invention is to pro-
vide a novel and improved device of this
20 general character including a main body or
container and in which are adapted to be
positioned trays or the like and wherein the
body or container is provided at its lower
portion with an air ingress opening and at
25 its upper portion with an air egress open-
ing, the trays or the like being positioned in-
termediate said openings and serving as
baffles whereby the air draft or current pass-
ing through the body or container travels in
30 a tortuous path so that an effective ventila-
tion is assured of the entire interior of the
body or container.

The invention consists in the details of con-
struction and in the combination and ar-
35 rangement of the several parts of my im-
proved lunch bucket whereby certain im-
portant advantages are attained and the de-
vice rendered simpler, less expensive and
otherwise more convenient and advanta-
40 geous for use, as will be hereinafter more
fully set forth.

The novel features of my invention will
hereinafter be definitely claimed.

In order that my invention may be the
45 better understood, I will now proceed to
describe the same with reference to the ac-
companying drawings, wherein:

Figure 1 is a view partly in side elevation
and partly in vertical section of a lunch
50 bucket constructed in accordance with an
embodiment of my invention.

Fig. 2 is a horizontal sectional view taken
substantially on the line 2—2 of Fig. 1.

Fig. 3 is a view partly in section and
partly in end elevation of my improved
bucket as herein embodied. 55

Fig. 4 is a fragmentary view in elevation
illustrating certain of the openings provided
in an end wall of the bucket as herein dis-
closed, and 60

Fig. 5 is a sectional view taken substan-
tially on the line 5—5 of Fig. 4.

As disclosed in the accompanying draw-
ings, B denotes the body of my improved
bucket which may be of any desired configu-
ration. In Fig. 2 of the accompanying draw-
ings, said body is shown as substantially ob-
long in top plan, but it is to be understood,
however, that the same may be of any other
design desired, such as oval or the like. 70

The upper face of the body B is open and
is adapted to be closed by the hollow mem-
ber M of a conventional type and which is
adapted to contain a supply of coffee or
other beverage or liquid, and said member 75
M has detachably engaged therewith in a
well known manner the cup C. The upper
end portion of the body B also has opera-
tively engaged therewith a handle member
H illustrated fragmentarily in Fig. 1 of 80
the accompanying drawings. This handle
member H may be of any type desired.

Supported within the body B and in ver-
tical spaced relation are the trays T which
are adapted to contain different articles of 85
food or the like, and each of the trays T is
of a length less than the length of the in-
terior of the body B so that said trays T,
when arranged within the body B, may be
disposed in staggered relation so that the 90
air currents or draft admitted within the
lower portion of the body B will travel
around said trays T in a tortuous path so
that the entire interior of the body B will
be effectively ventilated and thereby main- 95
tained in a highly sanitary condition.

One end wall 1 of the body B is provided
in close proximity to the bottom 2 with a
plurality of transversely disposed and
aligned air ingress openings 3 and which 100
openings are positioned below the lower
tray T when said tray is in applied position.
The entrance of air within the body B
through the openings 3 is under control of
the sliding valve or plate 4 and which plate 105
is provided adjacent one end portion with

an outstanding pin 5 extending through a slot 6 formed in the end wall 1.

The opposite end wall 1^a of the body B at a point above the upper tray T, when in applied position, is provided with the egress openings 3^a under control of the sliding valve or plate 4^a and which plate is adapted to be operated through the medium of the outstanding pin 5^a, as has just been referred to relative to the sliding valve or plate 4.

Each of the trays T, when applied within the body B, extends entirely across the interior of the body B so that the same serves as a baffle and the upper margins of the tray are defined by the outstanding flanges 7 and an end flange thereof extends within a channel 8 suitably positioned in the adjacent end wall 1 or 1^a. Each of the end walls 1 or 1^a at the desired distance below the channel 8 formed therein is provided at its opposite sides with the inwardly directed pins 9 upon which an end portion of a tray T rests and the opposite end portion of the tray rests upon a shoulder 10 formed at the lower portion of a pair of inwardly directed lugs 11 carried by the end walls 1 and 1^a. The lugs 11 inwardly of the shoulders 10 are provided with the upwardly and outwardly inclined walls 12, so that the positioning of the trays T within the body B is facilitated.

Each of the plates 3 and 3^a is suitably supported for sliding movement by the guideways 14 suitably secured to the inner faces of the end walls 1 and 1^a.

From the foregoing description, it is thought to be obvious that a lunch bucket constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in

carrying out my invention in practice except as hereinafter claimed.

50

I claim:

1. A lunch bucket comprising a body, inwardly directed members carried by the opposite walls of the body, certain of said members constituting lugs having their inner extremities provided with shoulders, each of said lugs inwardly of the shoulder being provided with an upwardly and outwardly inclined wall, and trays arranged within the body in vertically spaced relation and supported by the inwardly directed members, an end portion of each of the trays resting upon the shoulders of certain of the members.

60

2. A lunch bucket comprising a body, inwardly directed pins carried by the wall of the body, inwardly directed lugs carried by the opposed wall of the body, the inner end portions of the lugs being provided with a shoulder, each of said lugs inwardly of the shoulder having an upwardly and outwardly inclined wall, and a tray insertible within the body and of a length to rest upon the pins and the shoulders of the lugs.

65

3. A lunch bucket comprising a body, inwardly directed pins carried by the wall of the body, inwardly directed lugs carried by the opposed wall of the body, the inner end portions of the lugs being provided with a shoulder, each of said lugs inwardly of the shoulder having an upwardly and outwardly inclined wall, and a tray insertible within the body and of a length to rest upon the pins and the shoulders of the lugs, the wall of the body provided with the pins having a channel therein above the pins, the tray having a flange fitting within said channel when the tray is resting upon the pins and the shoulders of the lugs.

75

In testimony whereof I hereunto affix my signature in the presence of two witnesses.

OLIVER PIERCE GREENSTREET.

Witnesses:

H. H. HINTOR,
C. M. SARCHET.
